CONTROL MEANS FOR DRAFT REGULATORS

Morris W. Crew and George A. Short, Cleveland,
Ohio, assignors to The Hotstream Heater Com-
pany, Cleveland, Ohio, a corporation of Ohio

Application May 1, 1942, Serial No. 441,300

5 Claims.

(Cl. 236—45)

This invention relates to improvements in control means for draft regulators, particularly where they involve means for preventing the flow of cool air through heating equipment during the period when the burner is shut down.

An object of the present invention is to provide improvements for use with a draft stabilizer damper on the stack side of the furnace. Such a damper normally pivots freely in a thimble mounted on the furnace pipe or breeching, balancing the draft by means of a weight on the damper so as to maintain a predetermined furnace draft. An object of the present invention is to provide means for reducing the draft through the furnace to a minimum during inoperative periods of the burner or during those periods when automatic control means is not calling for the production of additional heat. The present device also provides for maintaining a short interval of normal draft after the burner is shut down for the purpose of carrying off products of combustion from the last increments of fuel burned during the demand period. This is particularly advantageous with oil burning equipment where normal operating draft is necessary for a short interval, generally between 10 to 15 seconds or more after the oil burner is shut off. At the same time our improved equipment provides for restoring the normal draft immediately upon a demand for additional heat from the furnace so that combustion is immediately resumed under the most favorable conditions, and puffing and "smoky start" is eliminated.

Another object of the present invention is to provide novel automatic equipment for producing the above named result by the use of a motor adapted to be stalled without injury, thereby providing equipment of a very simple form and adapted to be connected in electric circuits using customary or standard voltages without the necessity for special transformers and the like.

Other objects and advantages will appear from the accompanying drawings and description and the essential features will be set forth in the claims.

In the drawings, Fig. 1 is a vertical sectional view of the regulator along the line 1—1 of Fig. 5; Fig. 2 is a similar view showing another position of the parts; Fig. 3 is a fragmental view taken in a similar position to Figs. 1 and 2 and showing still another position of the parts; Fig. 4 is an enlarged fragmental view of certain of the parts of Figs. 1, 2 and 3, showing other positions thereof; Fig. 5 is a sectional view taken along the line 5—5 of Fig. 1; Fig. 6 is an enlarged

fragmental sectional view taken along the line 6—6 of Fig. 5; while Fig. 7 is a diagrammatic view illustrating one use of our improved device.

In the various views a furnace is shown at 10 having a draft pipe 11 connected with a stack 12. Our invention may be used whether the fuel is solid, liquid or gaseous, but in the present instance we have illustrated an oil burner 13 having a blower 14 which is driven through shaft 15 from motor 16. A very satisfactory means for controlling the draft for such a furnace regardless of the type of burner or fuel used in a draft stabilizing damper 17 pivotally mounted by means of a pivot 18 which works in side pockets 18a of the damper frame. Adjustable weights 19 and 20 balance the damper so that the draft acting in the direction of the arrow of Fig. 1 and tending to open the damper is balanced against the weights 19 and 20 so that the desired draft conditions are maintained in the furnace regardless of changing circumstances. Our improved device is arranged to permit this customary action to take place during such periods as the burner 13 is operating in response to a demand for additional heat while at the same time providing positive means for opening the damper 17 to a position of minimum draft and holding it open during stand-by periods when there is no demand for additional heat from furnace 10. This prevents the drawing of cold air through the furnace in the case of gas and liquid-fired furnaces and conserves the heat in the furnace setting during such stand-by periods. In the case of coil-fired furnaces it prevents the burning of the fuel bed faster than necessary during such stand-by periods.

Mounted at some convenient point near the damper 17 is a housing 21 in which is mounted a motor 22 of a type adapted while energized to be stalled without injury thereto. A satisfactory motor of this type is manufactured by Hansen Mfg. Co., Inc., and marketed under the name "Synchron," but motors satisfactory for the purpose are produced by others. The shaft directly driven by the motor is indicated at 23 in Fig. 6 and acts through a set of reduction gears 24 to drive the final shaft 25 at a very great reduction in speed as compared to the shaft 23. The reduction here may be of the order of approximately 1750 to 1. In other words, if the motor shaft 23 turns at 1750 R. P. M. then the shaft 25 will turn at about one revolution per minute.

Fastened to the shaft 25 so as to turn with it is the bell crank lever 26. One end of this lever carries the pin 27. The position of the parts

shown in Fig. 1 is what we have called the burner-operating position which permits damper 17 to swing freely in response to draft demands. The position of the parts shown in Fig. 2 corresponds to what we have called stand-by position and corresponds to the open position of damper 17 to provide minimum draft whenever heat is not being demanded of the furnace 10. In the position shown in Fig. 1, the pin 27 underlies and engages a hook 28a on the upper end of bar 28. This bar is mounted for vertically sliding and oscillating movement by means of a pin and slot connection. In the present instance a slot 28b in the bar 28 receives a pin 29 which is threaded into the housing 21. The lower end of bar 28 is connected by link 30 to the damper 17. It will be noted that the link fits loosely in the hole 28c of the bar and passes through an elongated slot 31a of an arm 31 which is rigid with damper 17. A wing nut 32 is threaded on the lower end of link 30 to adjust this connection as desired.

The motor 22 when energized moves lever 26 clockwise as viewed in Figs. 1 to 4 until lever 26 engages the stop pin 33. This position is maintained as long as heat is being demanded from the furnace. Upon deenergization of the motor 22 spring 34 moves lever 26 in a counterclockwise direction from the position of Fig. 1 to that of Fig. 2, lifting pin 27 and bar 28 and pulling upon link 30 to positively open damper 17 and hold it in the open position. It will be noted upon comparing Figs. 1 and 2 that when spring 34 in Fig. 1 is in its most extended position and therefore providing the greatest pull, it is working through a comparatively short effective lever arm as represented approximately by the horizontal distance between the center line of spring 34 and shaft 25. As the spring approaches the position of Fig. 2 and loses some of its tension, this effective lever arm increases so that the result is the application of a substantially constant torque on lever 26 by the spring 34.

It will be noted that as pin 27 moves from the position of Fig. 1 to that of Fig. 2 it travels in the arc of a circle and because of its engagement with the hook 28a, the upper end of bar 28 must follow the same arc, the bar meanwhile pivoting about the point 29. Means is provided to prevent the hook 28a on the upper end of bar 28 from following this arcuate path when pin 27 moves in a clockwise direction away from the position of Fig. 2 so as to cause pin 27 to very quickly clear the hook 28a, thus uncoupling the releasable coupling formed by pin 27 and hook 28a and permitting the bar 28 to drop promptly, restoring damper 17 to its normal stabilizing action. To this end we provide a latch or keeper 35 pivotally mounted in the housing at the point 36 and overbalanced for freely pivoting action in a clockwise direction until such movement is limited by engagement with the stop 37. A nose 35a is formed on the keeper so as to engage in front of the upper end of bar 28 as shown in Fig. 2 when the parts are in the stand-by position. The position of the parts as they are about to reach stand-by position is shown in Fig. 3. Here the upper end of bar 28 has engaged and lifted the nose 35a of the keeper and on further slight counterclockwise movement of lever 26 the parts will drop into the position of Fig. 2, at which time pin 29 engages the bottom of slot 28b. As the parts move out of this position upon energization of motor 22, the releasable coupling is uncoupled, since the pin 27 soon moves out of

the depression of hook 28a as shown in full lines in Fig. 4 and because the upper end of bar 28 is prevented by the keeper nose 35a from the following the pin 27. Thereupon the bar 28 starts to fall downwardly as shown in dot-dash lines in Fig. 4, under the influence of gravity. Thus very shortly after motor 22 is energized the damper 17 is released for its normal stabilizing action.

In Fig. 7 we have shown a diagram illustrating one use of our invention but in no sense limiting ourselves to such a use alone. In this view the motor 22 is supplied with current from the lines L₁, L₂ which may be the usual 115 volt supply found in many installations. The motor 22 is of a type to operate on this voltage. In one of the supply lines is illustrated a thermostat 38 which may be a room thermostat or the like for controlling the demand apparatus when heat is required from furnace 10. Connected in circuit is the motor 16 if such a motor is required either for driving a forced draft fan 14 or for driving a coal stoker or the like. In the case of a gas-fired furnace there might be no occasion for such a motor but our device would work as illustrated in Fig. 7 without any motor 16. In the case of a gas-fired furnace an electrical device for turning on the gas might be supplied in place of the motor 16.

The operation of our device in a typical installation would be as follows. When thermostat 38 closed the circuit of Fig. 7 in response to a demand for heat or more heat, the circuit would be completed through L₁, lines 39 and 40, motor 22, and line 41 to L₂. Motor 22 would start at the same time that the burner 13 started to operate. Almost immediately the parts would move as described in connection with Fig. 4 so as to uncouple the releasable coupling 27, 28a and release bar 28 which would drop immediately by gravity, causing link 30 to release damper 17 for its normal stabilizing action during the period when the burner was operating. When the parts reach the position of Fig. 1, the motor is stalled by the engagement of lever 26 against pin 33. When the demand for heat is reduced and thermostat 38 is thereby satisfied it breaks the circuit to motor 22, whereupon spring 34 starts to move the parts from the position of Fig. 1 to that of Fig. 2, it being realized that bar 28 is held on pin 29 so that pin 27 automatically engages beneath and is recoupled to the hook 28a in the burner-operating position of the parts. The swinging of lever 26 in a counterclockwise direction from the position of Fig. 1 to that of Fig. 2 is retarded because of the reduction gearing 24. It is impossible for spring 34 to back-wind the reduction gearing 24 very rapidly, so that the reduction gearing serves with the spring 34 as a time delay means, affording a brief period of the order of a quarter to one-half a minute required for the parts to move from the position of Fig. 1 to that of Fig. 2. This provides a short period of normal draft after burner 13 is shut down which is quite essential in the case of an oil-fired burner to prevent gassing back. When motor 22 is again energized, bar 28 is released from the position of Fig. 2 and drops immediately to the full extent of slot 28b, thus releasing damper 17 for the immediate provision of full draft required for furnace operation.

Our device is thus complete in one small unit, as exemplified in housing 21, which need only be mounted near the furnace and connected to any standard draft stabilizing damper such as

that indicated at 17 and the wires of a 115 volt system properly connected to motor 22. We have thus provided a very simple and efficient device adapted to operate over long periods without attention and adapted to provide excellent furnace operating draft conditions for furnaces using many different types of fuel.

Referring again to Fig. 7, a shunt line 42 may be provided around the thermostat. Switch 43 in this line would be normally open but might be closed by hand if normal draft were desired in the furnace, as for firing periods in a coal burning furnace. The parts would then move to the position of Fig. 1, regardless of thermostat 38, and normal draft would be established. Upon reopening switch 43, automatic control would be resumed.

What we claim is:

1. Control means for a furnace draft stabilizing damper, comprising an electric motor adapted while energized to be stalled without injury thereto, means operatively connecting said motor and said damper and having a stand-by position for positively holding said damper in a minimum draft position and also having a release position for release of said damper for normal draft stabilizing action, said connecting means comprising a lever operated by said motor and a bar connected with said damper and interengaging parts on said bar and lever automatically engaged when said parts are in release position and automatically disengaged when said lever leaves stand-by position, means for so disengaging them, spring means connected with said lever for moving the same to stand-by position, means for stalling said motor when said lever reaches release position, and means energizing said motor only when the furnace demands additional heat.

2. Control means for a furnace draft stabilizing damper, comprising an electric motor adapted while energized to be stalled without injury thereto, means operatively connecting said motor and said damper and having a stand-by position for positively holding said damper in a minimum draft position and also having a release position for release of said damper for normal draft stabilizing action, said connecting means comprising a lever operated by said motor to release position and a bar connected with said damper, said lever having a projection, said bar having a pin-and-slot mounting beneath said projection, said bar having at its upper end a hook overlying said lever projection when the parts are in release position, spring means for moving said lever to stand-by position whereby said lever projection is moved upwardly and lifts said hook and bar, keeper means engaging said bar in stand-by position, and said lever projection when leaving stand-by position moving in an arc adapted to release said hook whereby, after release, said hook and bar may fall freely.

3. Control means for a furnace draft stabilizer damper, comprising an electric motor adapted while energized to be stalled without injury thereto, means operatively connecting said motor

and said damper and having a stand-by position for positively holding said damper in a minimum draft position and also having a release position for release of said damper for normal draft stabilizing action, said connecting means comprising a lever oscillatable by said motor from a stand-by position to release position, said connecting means including reduction gearing, spring means for moving said lever from release position to a stand-by position, which movement is retarded by said gearing, said connecting means comprising disconnectible parts between said lever and damper, means causing disconnection of said parts by the first portion of said lever movement from stand-by position, whereupon gravity releases said damper for draft stabilizing action, said disconnectible parts being again connected upon reaching release position, and means energizing said motor only when said furnace demands additional heat.

4. Control means for a furnace draft stabilizing damper having operating and standby positions, comprising an operating element movable back and forth between two positions, motor means for moving it to one of its positions, power means for moving it to the other of its positions, operating connections between said element and the damper including a releasable coupling adapted when coupled and upon movement of said element toward one of its positions to cause movement of the damper to standby position and when uncoupled and upon movement of said element toward the other of its positions to release said damper for free movement to operating position, means for uncoupling said coupling when movement of said element toward its last mentioned position is initiated, and said motor means when effective energizing said power means and recoupling said coupling.

5. Control means for a furnace draft stabilizing damper, comprising an electric motor adapted while energized to be stalled without injury thereto, means operatively connecting said motor and damper and having a stand-by position for positively holding the said damper in minimum draft position and also having a release position for release of said damper for normal draft stabilizing action, said connecting means including reduction gearing, means operatively connected with said connecting means for moving the same to stand-by position against the inertia of said gearing, said connecting means also including disconnectible parts, means operative to disconnect said parts when said motor starts to move said parts from stand-by position toward release position, whereby said damper is then quickly released for normal draft stabilizing action, said parts being so constructed and arranged as to be again operatively connected when in said release position, means for stalling said motor when said connecting means reaches release position, and means energizing said motor only when the furnace demands additional heat.
